UNITED STATES PATENT OFFICE.

WILLIAM WOODWARD, OF CHICAGO, ILLINOIS.

EXPLOSIVE-ENGINE.

1,108,303.

Specification of Letters Patent. Patented Aug. 25, 1914.

Application filed May 19, 1913. Serial No. 768,588.

To all whom it may concern:

Be it known that I, WILLIAM WOODWARD, a citizen of the United States, and a resident of the city of Chicago, county of Cook, and State of Illinois, have invented certain new and useful Improvements in Explosive-Engines, of which the following is a specification.

My invention relates to improvements in explosive engines and especially to valves therefor and means for operating the same, the object of the invention being to provide an improved form of valve for such engines and improved means for operating the same.

15 The invention consists in the combinations and arrangements of parts hereinafter described and claimed.

The invention will be best understood by reference to the accompanying drawings forming a part of this specification, and in which,

Figure 1 is a vertical section, partially in elevation, of an explosive engine embodying my invention, Fig. 2, a section taken on line 25 $x-x$ of Fig. 1, and Fig. 3 is a section taken on line $y-y$ of Fig. 2.

The preferred form of construction as illustrated in the drawings comprises a cylinder 1 having separate semi-cylindrical sleeve sections 2 and 3 reciprocating therein. A piston 4 is arranged to reciprocate within sleeves 2 and 3 and is connected by means of a connecting rod 5 with the crank pin 6 of an ordinary crank shaft 7 mounted in crank case 8 in any suitable or desired manner. A cam shaft 9 is also arranged in crank shaft 8 and is geared to run at one-half of the speed of crank shaft 7, the engine illustrated being of the ordinary four-cycle type. Cam shaft 9 carries eccentrics 10 and 11 which are set thereon as shown and engage forks 12 and 13 respectively formed at the ends respectively of rock levers 14 and 15 as shown. Levers 14 and 15 are connected respectively with sleeve sections 2 and 3 by means of links 16 and 17, so that said sleeve sections will be reciprocated independently of each other by means of eccentrics 10 and 11 as will be readily understood by those skilled in the art. Supplemental valve cylinders 18 and 19 are formed at the head of cylinder 1 and in open communication therewith, cylinder 18 being provided with an exhaust port 20 and cylinder 19 being provided with an intake port 21 as will be readily understood. Spring ring valves 22

and 23 are arranged to reciprocate in cylinders 18 and 19 respectively and open and close ports 20 and 21 therein. These spring ring valves 22 and 23 are connected respectively with tongues 24 and 25 projecting upwardly from the ends of sleeves 2 and 3 respectively, and eccentrics 10 and 11 are so positioned on cam shaft 9 as to move sleeve sections 2 and 3 in proper relation to open and close said ports at the proper times as will be readily understood by those skilled in the art. For convenience in manufacture the upper ends of chambers 18 and 19 are closed by threaded plugs 26 and 27 and a suitable spark plug 28 is arranged in the head of cylinder 1 as will be readily understood. The form of valve disclosed constitutes a simple and effective one for the purpose and will be found to be highly efficient in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. An explosive engine comprising a crank case; a main cylinder secured at one end to said crank case; two valve cylinders arranged at the other end of said main cylinder in open communication therewith, said valve cylinders being provided with ports; a reciprocating valve in each of said valve cylinders, each of said valves being an annular member of resilient material split longitudinally thereof; a pair of sleeves in said main cylinder; an operative connection between each of said valves and one of said sleeves; a piston within said sleeves; a crank shaft in said crank case; and means in said crank case operatively connected with said crank shaft and arranged to operate said sleeves and valves, substantially as described.

2. An explosive engine comprising a main cylinder, a piston and coöperating parts; valve chambers independent of said main cylinder, in open communication therewith and provided with suitable ports; valves in

said valve chamber, each of said valves being an annular member of resilient material split longitudinally thereof; a crank shaft; and operative connections for said valves with said crank shaft passing through said main cylinder, substantially as described.

3. An explosive engine comprising a main cylinder, a piston and coöperating parts; independent reciprocating sleeve sections in 10 said cylinder, each of said valves being an annular member of resilient material split longitudinally thereof; two valve chambers arranged at the head of said cylinder in open communication therewith, there being 15 an exhaust port in one of said chambers and an admission port in the other; a valve in each of said chambers; a tongue on each of said sleeve sections engaging one of said valves; and means for reciprocating said 20 sleeve sections to control said valves and ports, substantially as described.

4. An explosive engine comprising a main cylinder, a piston and coöperating parts; independently reciprocating sleeve sections in 25 said cylinder surrounding said piston; two cylindrical valve chambers arranged at the head of said cylinder and in open communication therewith, there being an exhaust port

in one of said chambers and an admission port in the other; a valve in each of said 30 chambers; a tongue on each of said sleeve sections engaging one of said valves; and means for reciprocating said sleeve sections to control said valves and ports, substantially as described. 35

5. An explosive engine comprising a main cylinder, a piston and coöperating parts; independently reciprocating sleeve sections in said cylinder surrounding said piston; two cylindrical valve chambers arranged at 40 the head of said cylinder and in open communication therewith, there being an exhaust port in one of said chambers and an admission port in the other; a spring ring valve in each of said chambers; a tongue on each of said sleeve sections engaging one of said valves; and means for reciprocating said sleeve sections to control said valves and ports, substantially as described.

In testimony whereof I have signed my 50 name to this specification in the presence of two subscribing witnesses.

WILLIAM WOODWARD.
